United States Patent Office

Des. 220,560
Patented Apr. 27, 1971

220,560

BOTTLE

James H. Johnson, Princeton, N.J., assignor to Johnson & Johnson

Filed Jan. 30, 1970, Ser. No. 21,171

Term of patent 14 years

Int. Cl. D9—01

U.S. Cl. D9—118

FIG. 1

FIG. 2

FIG. 3

FIG. 1 is a top plan view of a bottle showing my new design.

FIG. 2 is an elevational view, the opposite side being the same in appearance as the side shown, and

FIG. 3 is a bottom plan view thereof.

I claim:

The ornamental design for a bottle, as shown and described.
